UNITED STATES PATENT OFFICE.

WALTER J. OWEN, OF CLEVELAND, OHIO, ASSIGNOR TO NANCY L. HOWARD
AND CURTIS C. HOWARD, TRUSTEES.

BRUSH-MAKING MACHINE.

SPECIFICATION forming part of Letters Patent No. 453,291, dated June 2, 1891.

Application filed January 16, 1891. Serial No. 378,044. (No model.)

To all whom it may concern:

Be it known that I, WALTER J. OWEN, a citizen of the United States, residing at Cleveland, in the county of Cuyahoga and State of Ohio, have invented a certain new and useful Improvement in Brush-Making Machines, of which the following is a specification.

My invention relates to a machine for producing brushes, and has particular relation to a machine producing an approximately feather-shaped brush, which is the subject of an application of even date herewith.

The objects of my invention are to produce a machine of this class by means of which the manufacturer will be enabled to produce with accuracy and speed a well-made, durable, and substantial brush of this kind of the desired shape, and to accomplish this object in a simple and inexpensive manner.

20 In the accompanying drawings, Figures 1, 2, and 3 respectively represent perspective views of the upper portions or heads of the different forms of standards used in my machine. Fig. 4 is a side elevation of my improved machine, showing a partially completed brush therein. Fig. 5 is a transverse section on line $x-x$ of Fig. 4, and Fig. 6 is a perspective view of the brush which is the product of the machine herein shown.

30 Similar letters refer to similar parts throughout the several views.

a , a' , and a^2 represent vertical standards, which are supported, as shown, in a horizontal row from a suitable bed-plate b . Each of said standards is provided with a flanged base, as shown at c , the latter being adjustably secured to the bed-plate b by bolts c' , which pass therethrough and extend through a longitudinal slot d , formed in the base b , said bolts being made to clamp the standards flanges firmly to the bed-plate or base by having affixed to their lower ends suitable nuts d' . Each of the standards a , a' , and a^2 is provided with approximately Y-shaped or forked upper end portions, which form crotches e , the latter being rounded at their bases, as shown.

As shown in Figs. 3 and 4 of the drawings, the forward standard a has the inner sides of its forks widened or extended in the direction of the length of the machine by forming there-

with suitable flat extending flanges, as indicated at e' . Projecting forwardly from each of the fork-arms of the standard a is a pin e^2 , having its outer end bent downwardly, as shown. The standards a' have, as indicated in Fig. 1 of the drawings, their fork-arms bent outwardly to form hook-shaped ends f . As shown in the drawings, I preferably employ five of the arms a' , arranged a short distance apart, one in rear of the other. For reasons hereinafter specified I preferably produce the standards a' of slightly varying heights, the height of said series of standards gradually decreasing from the central standards thereof. The standards a^2 , which are arranged in rear of the standards a' and at a distance apart, are preferably three in number, and, as shown in Fig. 2 of the drawings, have omitted from their fork-arms the hooks of the standard a' . Affixed to the bed-plate b , or to a table or suitable support upon which said bed-plate may be supported, is an angular binder holding-plate i , which consists of a horizontal flange i^2 , screwed to said bed-plate or support and a vertical flange arising therefrom, the latter being provided at intervals on its upper side with short vertical incisions, as shown at i^3 , said incisions being slightly V-shaped and adapted to receive and hold, as hereinafter described, a binder-strip.

As heretofore stated, the object of my invention is to facilitate the production of an approximately feather-shaped brush. (Shown in Fig. 6 of the drawings.) This brush, as indicated, is preferably formed of broom-straw, or what is ordinarily termed "hurl fiber," and the manner of producing the same by my improved machine is as follows.

The brush and brush-handle are formed integral, the same being formed by successive layers or bunches of stock laid one upon the other. The first or foundation bunch or whisk of fiber, as shown at g , is laid within the standard-crotches in such position that the heels or stems project slightly in rear of the rear standard a^2 , while the heads of the fiber project a distance beyond the front standard a . One end of the binder-strip k , which is preferably of rattan, is then tied about the whisk or bunch g , as indicated at k' . This having been accomplished, a few of the upper

straws of said foundation whisks are raised from the rear end portion of the latter in each hand, thus taking from said whisk *g* two smaller bunches or whisks which correspond with those shown at *m* in Figs. 4 and 5 of the drawings, which are shown in the advanced stage of manufacture. These smaller whisks *m*, which we will term the "plaiting-whisks," are turned forward from the tying-point *k'* and, passing on opposite sides of the fork-arms of the standard *a*, are caught, respectively, beneath the downturned or hooked ends of the pins *e*². The separated and forwardly-bent plaiting-whisks *m* are supported in this position until a new bunch *g'* of fiber is laid upon the first bunch, and the binder *k* is given a turn about said new bunch *g'* and the foundation bunch *g*, as shown at *g*², thus binding the new fiber bunch to the old. The binder-strip is then drawn tight about said fiber bunch and held in this position by pressing the binder-strip in one of the V-shaped notches or incisions *i*³ of the holding-plate *i*. The plaiting-whisks *m* are then detached from the pins *e*² and pressed to the rear over the last coil of the binder-strip. In order to prevent the rear portions of the plaiting-whisks from springing upward, which might be caused by the bend previously formed therein, they are temporarily pressed on the outer sides of the fork portion of the rear standards, where they engage with the shoulder formed in the production of said forked portions. This having been accomplished, two new plaiting-whisks are, as previously described for the lower bunch, taken from the new or upper bunch and supported in the manner before described until a new bunch of fiber has been laid upon said upper bunch and bound to the lower bunches, as hereinbefore described, when said new plaiting-whisks are turned to the rear over said last coil of the binding-strip. This method of binding bunch upon bunch of the fiber and plaiting with each bunch the whisks *m* is continued until the desired number of fiber bunches have been bound together, when the rear-end portions of the plaiting-whisks which are caught against the outer sides of the standards, as described, are drawn inward upon the stems or handle portion *n* of the brush.

As shown in the drawings, the fiber bunches which form the body of the brush are so laid, one upon the other, as to cause a gradual inclination of the forward or brush ends of the fiber to the rear, thus imparting to the brush-head *p* an approximately feather-blade outline. (Shown in Fig. 6.) As the points at which the whisks are bound are equidistant from the ends thereof, it will be seen that the winding of the binding-strip will be continued spirally and the coil of the binder-strip will be made a step nearer the end of the brush. As the manufacture of the brush continues it will be seen that the holding of the plaiting-whisks may be accomplished by

engaging the latter with one or more of the hooks *f* of the standard-heads *a'*. A sufficient number of brush-composing fiber bunches having been laid and bound together, as above described, the stems, or those portions of the fibers in rear of the brush-head, are bound together by the continued winding about the same of the binder-strip, thus forming a rounded handle *n*. The end of the handle portion having been reached, the end of the binder-strip is fastened by inserting it one or more times through the body of the handle, as shown at *q'* in Fig. 6. 80

From the construction shown and described it will be seen that the series of standards not only serve to support the brush while the same is being formed, but that the pins *e*² of the standards *a* and the fork-hooks of the standards *a'* serve to hold the plaiting whisks or bunches in a desirable position while the binding of the parts is accomplished. The varying heights of the standards or depths of the crotches thereof admit of the brush-handle and the back of the brush-head having the desired curve or curves imparted thereto, said curves resulting from the pressure of the stalk within the standard-crotches. 90

My improved machine being formed, as shown and described, of separated standards, it will be seen that a sufficient finger-space may be left between the standards to admit of the handling and binding of the parts of the brush and at the same time provide a support for the latter. It is also obvious that by loosening the nuts *d'* the standards may be moved upon their bed-plate to increase, if desired, the distance between them, the slot *d* forming a guide for the bolts *c'*, and serving to hold the standards in proper alignment. 100

Having now fully described my invention, what I claim, and desire to secure by Letters Patent, is—

1. In a machine for forming hand-brushes, a series of separated vertical standards of varying heights, said standards being provided with forked heads, said fork-crotches being in alignment, as described, substantially as specified. 115
2. In a machine for forming brushes, a series of vertical standards arranged in a row, one in rear of the other, as described, each having a forked head and flanged base, of a horizontal bed-plate to which said standards are detachably and adjustably supported, substantially as described. 120
3. In a brush-making machine, the combination, with a series of vertical standards arranged one in rear of the other, said standards having forked heads and flanged bases, as described, of a horizontal bed-plate, a longitudinal slot in said bed-plate, bolts passing through said standard-bases, and a bed-plate slot and nuts on the lower ends of said bolts, substantially as described. 125
4. In a machine for making hand-brushes, the combination of a series of vertical stand-

ards supported from a suitable bed-plate, one in rear of the other, as described, said standards having forked heads and hooks f^2 , formed on a portion of said fork-arms, substantially 5 as described.

5. In a machine for forming hand-brushes, the combination, with a series of vertical standards adjustably and detachably supported from a suitable bed-plate, and arms 10 ranged one in rear of the other, as described, of angular pins e^2 , projecting from the arms of the forward standard-fork, and fork-arm hooks formed, as described, on a portion of said standards, substantially as and for the 15 purpose specified.

6. The herein-described method of forming the hand-brush, consisting of binding one

upon the other at approximately equidistant points from their ends successive bunches of fiber, said binding being produced by spirally winding about said bunches a suitable binding-strip of rattan or similar material, plaiting, as described, with each of said bunches, two plaiting-whisks formed from the fiber stems and forming the rounded handle 20 portion of said bunch by a continuation of the spiral winding of the binding-strip about the fiber stems and about the rear end portions of the plaiting-whisks, substantially as specified.

WALTER J. OWEN.
